GUTTER HANGER

Howard B. Feltman, Wyncote, Pa., assignor to
 Berger Brothers Company, Philadelphia, Pa.,
 a corporation of Pennsylvania

Application February 24, 1933, Serial No. 658,423

1 Claim. (Cl. 108—29)

My invention relates to improvements in fixtures of the type employed for suspending drain gutters or troughs under the eaves of buildings, and the object of my invention is to provide a hanger fixture of the stated character which may be attached to the supporting structure more rapidly and with greater safety, and which may be more readily and accurately aligned than the corresponding fixtures of the prior art.

10 In the attached drawings:

Figure 1 is a view in perspective of a hanger fixture made in accordance with my invention;

Fig. 2 is a fragmentary sectional view showing the manner in which the fixture shown in Fig. 1 is attached to the supporting structure;

Fig. 3 is an enlarged sectional view illustrating a detail of the fixture;

Figs. 4, 5 and 6 are views in perspective of fixture plates corresponding to that shown in Fig. 1 and illustrating modifications of this element within the scope of the invention;

Fig. 7 is a view in perspective of another form of hanger fixture made in accordance with my invention;

25 Fig. 8 is a fragmentary side elevational view illustrating the manner in which the fixture shown in Fig. 7 is attached to the supporting structure, and

Fig. 9 is a section on the line 9—9, Fig. 7, and 30 shows in addition a portion of a support structure to which the fixture is attached.

With reference to Figs. 1, 2 and 3 of the drawings, I have therein illustrated a well known form of fixture employed for suspending drain troughs or gutters to the eaves of buildings. This fixture, known in the trade as a shank, comprises in the illustrated form a plate 1 to which is attached a depending stem 2. In the present instance a tongue 3 is pressed out of the body of the plate at right angles thereto, and the stem 2 is attached to this projecting tongue by means of a rivet 4. The plate 1 is provided at its vertical edges with apertures 5 for reception of nails or other elements by means of which the plate is secured to the eaves of the building, as illustrated in Figs. 2 and 3, the supporting structure being designated by the reference numeral 6. The stem 2 of the shank in the present instance takes the form of a channel having a series of openings 7 providing for passage of bolts or rivets (not shown) by means of which a gutter-supporting circle may be attached to the shank, as indicated by broken lines. The general form and manner of use of this device is well known in the art and 55 requires no further description.

The operation of attaching fixtures of this character to buildings must frequently be conducted from a ladder. The shanks are generally spaced from two to three feet apart, and it is the natural and common practice for a workman to attach as many shanks from one position of the ladder as may be possible, to thereby avoid the necessity of numerous readjustments of the ladder. Even at best, the position of the workman is apt to be awkward or constrained, and since it 5 is necessary to hold the shank as well as the attaching nails in one hand to thereby leave the other hand free to wield the hammer, the operation is usually a slow one and frequently dangerous. Working under the disadvantageous conditions, it is also extremely difficult to accurately locate the shank in the structure in its properly 10 aligned position preparatory to driving the securing nails, and since accurate alignment of the shanks is highly important by reason of the 15 necessity for maintaining the proper grade of the gutter, the shank-securing operation is still further complicated. Also by reason of the difficulty 20 of locating the shank preparatory to driving the securing nails, it frequently happens that the 25 shank or nail slips from the hand, with attendant annoyance and loss of time.

By my invention, I have provided simple, inexpensive and highly effective means for overcoming in large degree these many disadvantages. 30 The operation of attaching the shank to the supporting structure is greatly facilitated, the danger involved is reduced, and the accuracy of the work improved.

With reference to Figs. 1, 2 and 3 of the drawings, it will be noted that I have punched out of the plate 1, approximately at the center thereof and projecting at the side opposite that from which the stem 2 is attached, a pointed teat 9, the plane of this teat in the present instance 35 lying substantially in the plane with the long or horizontal side of the plate. This teat, which is a fixed part of the shank structure, constitutes a means whereby the plate 1 and, in fact, the entire shank may be readily and accurately 40 located or fixed in the supporting structure prior to the driving of the nails or other permanent securing elements through the holes 5. In attaching the shank, it is unnecessary to utilize any 45 of the permanent securing elements which form no fixed part of the shank, since by placing the shank in its proper position against the supporting structure with the pointed teat 9 in contact with the latter, and by thereafter striking 50 with a hammer the opposite face of the shank 55

at a point opposite the teat 9, this teat is made to penetrate the wood of the supporting structure to thereby definitely locate or fix the shank in the supporting structure preparatory to the driving of the nails or other permanent securing elements through the apertures 5. While the teat 9 is capable of firmly retaining the shank in position upon the structure prior to the driving of the securing nails, it still permits minor angular or other adjustments of the shank into a properly aligned position before the permanent securing elements are driven. In this respect, the device permits inspection and accurate adjustment of the shank before the permanent securing elements are applied.

This device while simple in form effects a substantial improvement in the characteristics of the fixture, in that it greatly facilitates the operation of attaching the fixture to the eaves, renders alignment of the fixture a relatively simple matter, and generally reduces the hazards involved in attaching fixtures of this character.

It will be apparent that the invention in principle is capable of other embodiments than that described above, and in Figs. 4, 5 and 6, I have illustrated modifications in the shank within the scope of the invention. In Fig. 4, the single teat 9 of the previously described embodiment is replaced by a pair of teats 11, 11 located at the center of the upper and lower edges of the plate; the plate shown in Fig. 5 is provided with four teats 12 located respectively at the four corners of the plate; while in the embodiment shown in Fig. 6, the two teats 13 are stamped out of the material of the plate after the manner of the teat 9 in the embodiment first described, but the teats 13 in this instance are so located that the openings 14 left in the plate by displacement of the teats 13 may constitute apertures for reception of the permanent securing elements. A series of such apertures are desirable by reason of the added simplicity of attaching the device to the structure, wherein conditions frequently are such as to prevent the use of one or more of the apertures for nailing purposes.

My invention also applies to other forms of fixture than that shown in Figs. 1 to 6 of the drawings, and another type of fixture for the same purpose is illustrated in Figs. 7 to 9, inclusive. The fixture in this instance takes the form of a curved shank 15 which is adapted to be attached, as shown in Fig. 8, to the inclined roof beams 16. The gutter-supporting circle 17 is attached to the depending portion of the shank 15 in the manner previously described in connection with the embodiment shown in Figs. 1, 2 and 3. With reference to Figs. 7 and 9, it will be noted that the shank 15 is provided with a pair of punched-out and preferably pointed teats 18, which are adapted to penetrate the wood of the supporting structure 16 to locate or fix the shank therein preparatory to driving of the permanent securing means. The advantages of the invention in its application to this form of fixture are similar to those previously set forth.

It will be understood that there may be still further modifications and applications of my invention to fixtures of this general character without departure from the invention.

I claim:

A gutter hanger fixture of the type comprising a plate adapted to be secured against an exposed surface of an eaves structure underneath the roof overhang, said plate having apertures for passage of securing elements therethrough, said fixture comprising also a stem at one face of and depending from said plate and adapted to receive a gutter-supporting circle, and a projection on the opposite face of said plate located adjacent said apertures and in substantial alignment with the stem whereby impact on the latter is transmitted by direct thrust to said projection to cause the projection to penetrate the eaves structure to thereby fix the fixture in a normal permanent position preparatory to entering said securing elements, said projection being above the center of weight of the entire fixture.

HOWARD B. FELTMAN. 45
